UNITED STATES PATENT OFFICE.

THOMAS ALBERT BRIGGS CARVER, OF LONDON, ENGLAND.

PATTERN-CONTROLLED SHEDDING MECHANISM.

Application filed July 10, 1923, Serial No. 650,712, and in Great Britain September 8, 1922. Renewed April 21, 1927.

This invention relates to the weaving of damask and kindred fabrics and in particular to the method of controlling the warp for the development of the pattern and twill, 5 and has amongst its principal objects the removal of certain limitations and the reduction of cost inherent in the use of the usual jacquard machine which, in one or other of its forms is employed when the pattern is 10 of such complexity as to require a larger number of heddles than can conveniently be accommodated in the loom.

According to the present invention the shedding mechanism is grouped in separate 15 self-contained rows of thread lifting actions determining electrically from a pattern plate whether a thread is to be a ground thread or a pattern thread, so that the self-contained rows can be arranged interchangeably and 20 adjustably in any desired relation to the warp, all the rows being subject to common lifting mechanism for the shed and to common mechanical control of the twill through twilling mechanism engaging corresponding 25 selecting actions in each group.

With this grouping of the thread-lifting actions it becomes possible, e. g. to obviate the necessity of mounting jacquard machines high above the warp consequent upon the 30 needles having to be controlled by a card of definite area and the consequent long mechanical connections required to convey the necessary lifting movements, since the selecting mechanism can be arranged to be easily 35 accessible from the floor to control the warp threads without the intervention of the long harness otherwise required for transmitting the action of the hooks to the particular threads in the warp which it is their duty to 40 control. In this case there is provided for each thread a selecting action contained in a group which can be mounted adjacently above the warp threads which it controls and within a horizontal space not greater than 45 that occupied by these threads. For example, a group of selecting actions for 40 threads can be constructed to occupy no more than $\frac{1}{16}$ of an inch laterally. It is thus possible by such means to control 128 threads 50 per inch or any less number, the groups of selecting actions being mounted to permit of lateral spacing.

Secondly, it is possible to eliminate the reversal of twill which is inherent in all

cloths with a turn-over repeat in which the 55 twill is performed by a jacquard machine, because by choosing for the number of selecting actions composing a group a multiple of the twills most generally in use, e. g. 40, I can bring all the selecting actions for say 60 every fifth or every eighth thread into one line from side to side of the loom and so easily subject them to a control common to all the fifth or eighth threads throughout 65 the width of the cloth, thereby securing the same effect as heddles in the heddle and harness system of weaving.

Thirdly, to secure the advantages of what is known as the self-twilling system without foregoing the possibility (unavailable in present jacquard machines) of the twills in the ground and in the figure or pattern being run in opposite directions or being changed to different twills as may be required for 70 different qualities of cloth woven in the same loom, I provide the selecting action for each thread with two lifting members which I shall call the ground lifter and the pattern lifter and upon which respectively the ground twill and the pattern twill are performed, and I arrange the action which 75 determines whether a thread is to be a ground thread or a pattern thread to engage the thread with the ground lifter or with the pattern lifter, as the case may be; or I may provide a single lifting member which can 80 operate alternatively as a ground lifter or a pattern lifter. The actions controlling the two twills are quite independent and consequently the two twills may be the reverse of 85 one another, or they may each of them be of any leaf which the particular quality of the cloth may demand, so long as it is within the scope of the number of selecting actions 90 in one group.

Fourthly, the actions determining whether the threads are to be ground threads or pattern threads are electrically controlled and I am thus enabled to take advantage of the great economy effected by the well known method of reading through feelers, one for 100 each selecting action or one for two or more selecting actions, as desired, equally spaced in a row with their ends extending in a straight line across and touching in proper synchronism with the plate movements and current changes a metallic plate upon which the pattern appears as conducting and the 105

ground as non-conducting material, or conversely.

Further, to secure the advantages inherent in what is known as the semi-open shed in weaving, I provide in each selecting action lifting members arranged in pairs which are either themselves raised and lowered respectively by two members which reciprocate vertically in substantially simple harmonic motions of the same period but in opposite phase, or control the raising and lowering of the parts hereinafter referred to as pattern selectors. These lifting members co-operate with two vertically guided but relatively free members known as the pattern selectors, which in turn are correlated with a member vertically guided, e. g. in the pattern selectors themselves, and suitably attached to the warp thread. The pattern selectors have vertical slots of the same length approximately as the lift, so that they can impart to the common member before mentioned, which may be called the common lifter, the same motion as the tail connected with a pair of hooks in a double lift jacquard machine.

In certain instances the limitations in regard to the turn-over of the twill and the employment of harness may be admissible, and in such cases the appropriate number of groups of selecting actions may be mounted as a warp controlling machine high above the warp in the manner in which jacquard machines are employed at present, the operations controlled by the groups of selecting actions being effected through the usual harness employed in looms using ordinary jacquard machines.

In this method of using the present invention, as in that hereinbefore referred to, the shedding mechanism is grouped in separate self-contained rows of thread-lifting actions determining electrically from a pattern plate whether a thread is to be a ground thread or a pattern thread, so that the self-contained rows can be arranged interchangeably and adjustably in any desired relation to the warp, all the rows being subject to common lifting mechanism for the shed and to common mechanical control of the twill through twilling mechanism engaging corresponding selecting actions in each group.

A machine constructed in accordance with my invention is illustrated in the accompanying drawings, Fig. 1 being a perspective view of the general arrangement of the essential parts; Fig. 1^a a similar view of one of the groups of selecting actions with cover plate removed; Figs. 2 and 3 perspective views on an enlarged scale showing alternative arrangements of the selecting action for one thread; Fig. 4 a further modification of same; Fig. 5 a detail in perspective; and Fig. 6 a perspective view illustrating a modified application of the invention.

Referring first to Figs. 1, 1^a and 2, the

machine comprises an appropriate number of groups R (Fig. 1) of selecting actions. These groups, of which only eight are shown in Fig. 1 for the sake of clearness, are supported on a frame S above the warp at a height accessible to the operator from the floor and laterally adjustable thereon in the slot T, this frame also carrying the twilling bars Q (Figs. 1, 2 and 3) and their controlling mechanism U, together with rocking or reciprocating members V to convey the lifting action from the loom shaft to the lifting members M (Fig. 1^a) in the groups of selecting actions.

The machine comprises also the reader frame or pattern mechanism containing the row of feelers W and the mechanism for appropriately feeding the metallic pattern X, and the feelers are connected with the coils of the individual magnets J in the selecting actions by groups of flexible conductors Y which enable any feeler to be connected with any one or more selecting actions. In this manner I am enabled to perform the selection between pattern and ground for any portion or portions of the warp from any section of the metallic pattern, securing the advantages at present obtained by repeats, whether straight or reversed, that is to say, from the same section of the metallic pattern I can, by connecting the same feelers with selecting actions in different parts of the warp, repeat the same section of the design one or more times as desired to read either from right to left or from left to right. By these means, just as in ordinary practice the use of straight or reversed repeats enables the cloth to be covered with pattern from a smaller number of cards, the cloth can be covered with pattern from a smaller pattern plate.

As shown in Fig. 2, I pass each thread of the warp A through a mail B in the usual manner and I employ the usual hingoe C or a spring to return the thread to its lowest position. I connect the mail above the warp, either directly or preferably through a coupling D so as to enable the groups of selecting actions to be removed without the necessity of cutting out the warp, with what I have referred to as the common lifter E, which may consist of a thin narrow flat plate guided in the frame of the group of selecting actions so as to have only one degree of freedom, viz in an approximately vertical line through a range equal to the lift, and I provide at the top of this lifter a pin E' or other suitable engaging device which projects an equal distance at right angles to the surface of the plate on each side of the lifter into the slots in the pattern selectors F', F^a which may be conveniently arranged as plates of the same width as the common lifter one on each side of the common lifter, so as to have one degree of freedom of move-

- ment parallel with that of the common lifter. The length of the slots in the pattern selectors F' , F^2 and the position of their ends relatively to the pin E' in the common lifter E are such that supposing the two pattern selectors to be given simple harmonic motion in a vertical line in phases half a period displaced from one another, they will perform upon the common lifter and therefore upon the thread of the warp, the same action as is performed upon a thread by any pair of hooks controlling the same thread in a double lift jacquard machine.

Each pattern selector in the construction of Fig. 2 is provided with an armature G' , G^2 , a projection G^o from which is arranged to engage with the pattern lifter H' if the armature is attracted to the magnet J excited by current from the metallic pattern, and with the ground lifter H^o if the armature is not attracted by the magnet against the force of a spring tending to keep it in that position; the pattern and ground lifters consisting conveniently of plates of half the breadth of the pattern selectors so as to be accommodated with one degree of freedom in a vertical line in the same direction as the pattern selectors and common lifter. The ground and pattern lifters are provided at their upper ends with upwardly projecting hooks K or similar engaging devices which engage and disengage with corresponding hooks or projections L at the lower edge of a common lifting bar M which, by means of rack V^o and pinions V' (Fig. 1) or by any other convenient driving device is given reciprocating motion in a vertical line to produce the appropriate shed in the warp.

I have already referred to the performance of the twill in the ground and figure respectively by a twilling action upon the ground lifter for the ground twill and upon the pattern lifter for the pattern twill. This action I will now describe. Within a short distance from the lower end of its range of vertically reciprocating motion each common lifting bar M with its downwardly projecting hooks L is deflected, as for example by means of a spring (not shown in Figs. 2, 3 and 4 of the drawings) in conjunction with the shaped frame bar N , slightly in a horizontal direction and continues its downward movement in a new vertical line in which the engaging portions of the hooks L are clear of the engaging portions of the hooks K of the lifters. Now if, when the common lifting bar M returns upwards through the same path the engaging portions of the hooks of the ground or pattern lifters are above the engaging portions of the hooks, on the lifting bar when the lifting bar is deflected back into the line of the greater part of its vertical movement, the hooks on the common lifting bar will engage the hooks of the ground or pattern

lifters, but if the engaging portions of the hooks on the ground or pattern lifters are below that point, the hooks of the lifting bar will not engage the hooks on the ground or pattern lifters. I can thus determine whether any ground or pattern lifter is to be raised by the common lifting bar or not by controlling the position of its hook in a vertical line during this part of the cycle, and this I do by allowing the ground or pattern lifter to rest upon a projection O (Fig. 2) from lift control bars O' , O^2 arranged vertically above the ground or pattern lifters and extending upwards through the frame of the group of selecting actions, such extensions being represented by pins Z in Fig. 1. The lift control bar is caused by a spring P always to tend to raise the ground or pattern lifter into the position in which its hook will be engaged by the corresponding hook on the common lifting bar when the latter is deflected horizontally, but a downward force at its upper end will depress the spring of the lift control bar and allow the ground or pattern lifter to take up the position in which its hook, when the common lifting bar passes through the engaging point, will not be engaged. The portions Z of the lift control bars which project upwards through the frame of the group are so disposed that a straight twilling bar Q running from side to side of the loom can effect the downward movement on all and only corresponding lifters in each group. In Fig. 1 three such twilling bars Q are shown, the remainder being indicated. I may employ any convenient movement to give the downward movement of the twilling bars, for example, I may provide in them slots a , Fig. 1, at an angle approximately of 45° to the vertical, and I may mount the bars on stationary rods b passing through these slots, so that a horizontal movement at the ends of the twilling bars will give the downward movement to depress the row of lift control bars. Through the agency of a pegged drum U or by an ordinary punched card or by a drum drilled with suitably distributed holes, or other convenient selecting arrangement, I give the horizontal movement to the twilling bars, which may be returned by a spring, to produce the desired twills in the ground and figure.

I can now describe the action taking place in any group of selecting mechanisms. From the shaft of the loom, I drive a rocking bar or rack V^o , Fig. 1, or similar driver, to and fro from front to back of the loom and from this horizontal reciprocating movement rotary movement is imparted to pinions c driving the racks c^o or other convenient driving device to produce in the common lifting bar M with its downwardly projecting hooks L the vertically reciprocating move-

ment through a range to give the appropriate shed in the warp. Each group of selecting mechanisms has, as I have already described, two common lifting bars M moving with approximately simple harmonic motion in a vertical line in phases half a period displaced from one another. Considering, however, the action on any one lifting bar, through the agency of the twilling bars 10 Q and the lift control bars O', O², the ground and pattern lifters will be raised in accordance with the twill desired, that is to say, for example, if a 5 leaf twill is to be performed upon the ground and an 8 leaf 15 twill upon the figure, any ground lifter will be raised once in every five shots and any pattern lifter will be raised for every shot except every eighth. When the lifters H', H² with their corresponding pattern selecting 20 tors F', F² are about at the lower end of their range, the pattern selecting action operates, that is to say if the corresponding feeler is in contact with a metallic portion 25 of the pattern plate, the corresponding magnet will be energized and the corresponding armature will be attracted to engage the pattern selector with the pattern lifter, and if the feeler is in contact with an insulated portion of the pattern plate the spring return 30 will cause the armature to engage the pattern selector with the ground lifter. Through the agency therefore of the common lifter E a warp thread will be raised at every upward movement of the common lifting bars, except every eighth, if its feeler 35 is in contact with a metallic portion of the pattern plate, and it will be raised by every fifth upward movement of the common lifting bar if its feeler is in contact with an 40 insulated portion of the pattern plate.

As I have already described, the common lifter is acted upon by a pair of pattern selectors and in the construction of Fig. 2 by two pairs of ground and pattern lifters to 45 produce the same action as that of a double lift machine, and the twilling bars Q controlling the two pairs of lift control bars O', O² for each thread are so actuated from their selecting arrangement as to produce 50 among the alternately rising and falling pairs of ground and pattern lifters the twill desired, for example 5-leaf in the ground and 8-leaf in the figure.

The same selecting action may be achieved 55 by the alternative arrangement of parts shown in Fig. 3. Here the twilling bars Q impart to the pattern and ground lifters H', H² the same movement as is imparted in Fig. 2 to the lift control bars O', O² and the armature G is mounted on a lift control bar O² (Fig. 3) instead of upon the pattern selectors F', F². At their upper ends the selectors F', F² terminate in hooks engaging them with the common lifting bar 60 in the same way as the pattern and ground

lifters are engaged in Fig. 2; the pattern and ground lifters and the armature thus move only through a range sufficient to give the engaging action between the selectors and the common lifting bar instead of 70 through the whole range of vertical movement as in Fig. 2.

In the modified construction shown in Fig. 4 of the accompanying drawings the armature G is fulcrumed on a stationary pin G' in the frame, instead of upon a pin moving with the lift control bar O², and has at its lower end a pin G⁰ which, by the movement of the armature G towards and away from its magnet, shifts to one side or the other a rocker O⁴ pivoted on the lift control bar O² when the latter is carried downwards to the end of its range by the vertically reciprocating member M, and when the lift control bar is urged upwards again by the spring P it is allowed to rise or not, according as the twilling bar Q then in register with the upper end of the rocker O⁴ is raised or lowered in its path.

The movement of the bar M to cause the engagement and disengagement of the hooks L and K may be effected by the means shown in Fig. 5, in which the bar M is mounted to slide horizontally in the vertically reciprocating guide bar M', this movement being communicated to the bar M through a lever r pivoted on a downward extension s from the guide bar M'. When the latter is driven downwards by the reciprocating mechanism the lower part of the lever r strikes upon a roller t journalled in the frame and moves the bar M into the position in which the hooks are out of engagement. As the guide bar M' rises again the bar M is returned by the spring u to the position in which the hooks engage each other.

In the arrangement shown in Fig. 6 corresponding parts are indicated by the reference characters employed in Figs. 1-5. In this arrangement the groups of selecting actions R are mounted as an ordinary jacquard high above the warp and the operations which they control are effected by means of the harness indicated generally by 110 I which is usually employed with ordinary jacquard machines and which in the apparatus of Fig. 6 connects the mails B above the warp either directly or through a coupling with the common lifters E of the selecting actions R.

Having thus described the nature of the said invention and the best means I know of carrying the same into practical effect, I claim:

1. In apparatus for the weaving of damask and the like, lifting actions controlling each separate thread and grouped in separate laterally adjustable self-contained rows, selecting elements in said lifting actions, and

means for operating electrically said selecting elements to effect the selection between pattern and ground.

2. In apparatus for the weaving of damask and the like, lifting actions controlling each separate thread and grouped in separate self-contained rows which are interchangeable and adjustable laterally with respect to the warp, selecting elements in said lifting actions, twilling mechanism engaging corresponding selecting elements in each group of thread-lifting actions, and a common mechanical control of the twill in the pattern and in the ground independently operating through said twilling mechanism.

3. In an apparatus for the weaving of damask and the like, lifting actions controlling each separate thread and grouped in separate self-contained rows which are interchangeable and adjustable laterally with respect to the warp, selecting elements in said lifting actions wherein the selecting action for each warp thread comprises a ground lifter and a pattern lifter, means for operating said ground and pattern lifters according to the twill in the ground and pattern respectively, means whereby the ground and pattern lifters are alternately engaged with the thread in accordance as to whether it is to be a ground thread or a pattern thread, twilling mechanism engaging corresponding selecting elements in each group of thread-lifting actions, and a common mechanical control of the twill in the pattern and in the ground independently operating through said twilling mechanism.

4. In an apparatus for the weaving of damask and the like, lifting actions controlling each separate thread and grouped in separate self-contained rows which are interchangeable and adjustable laterally with respect to the warp, selecting elements in said lifting actions wherein the selecting group for each warp thread comprises a ground lifter and a pattern lifter, means for operating said ground and pattern lifters according to the twill in the ground and pattern respectively, means whereby the ground and pattern lifters are alternately engaged with the thread in accordance as to whether it is to be a ground thread or a pattern thread, said latter means being electrically controlled, twilling mechanism engaging corresponding selecting elements in each group of thread-lifting actions, and a common mechanical control of the twill in the pattern and in the ground independently operating through said twilling mechanism.

5. In an apparatus for the weaving of damask and the like, lifting actions controlling each separate thread comprising a lift

bar operating alternatively as a ground lifter or as a pattern lifter, the lifting actions being grouped in separate laterally adjustable self-contained rows, a control element, ground twilling and pattern twilling mechanism, and means whereby the control element is brought into operative relation with said ground twilling or pattern twilling mechanism.

6. In an apparatus for the weaving of damask and the like, lifting actions controlling each separate thread comprising a lift bar operating alternatively as a ground lifter or as a pattern lifter, the lifting actions being grouped in separate laterally adjustable self-contained rows, a control element, ground twilling and pattern twilling mechanism, means whereby the control element is brought into operative relation with said ground twilling or pattern twilling mechanism, and a pattern plate from which the control element is electrically operated.

7. In an apparatus for the weaving of damask and the like, thread lifting actions controlling each separate thread and grouped in separate laterally adjustable self-contained rows, the rows of thread lifting actions being mounted adjacently above the threads which they control, selecting elements in said lifting actions, and means for electrically operating said latter elements to effect the selection between pattern and ground.

8. In apparatus for weaving damask and like fabrics, lifting actions controlling each separate thread and grouped in separate self-contained rows, selecting elements for each warp thread in said lifting actions comprising a ground lifter and a pattern lifter, means for operating said ground lifter and pattern lifter according to the twill in the ground and pattern respectively, and electrically controlled means whereby said ground lifter and pattern lifter are alternately engaged with the thread.

9. In an apparatus for weaving damask and like fabrics, lifting actions controlling each separate thread, selecting elements in said lifting actions comprising a lift bar, operating alternatively as a ground lifter or as a pattern lifter, and a control element, ground twilling and pattern twilling mechanism, a pattern plate, and electrical means controlled by the pattern plate whereby the control element is brought into operative relation with said ground twilling or pattern twilling mechanism.

In testimony whereof I have signed my name to this specification.

THOMAS ALBERT BRIGGS CARVER.
